Patented Nov. 3, 1970

219,100

BOX FOR CANDY OR THE LIKE

Amilcare Dogliotti, Alba, Italy, assignor to P. Ferrero
& C. S.p.A., Alba, Italy, an Italian joint-stock company

Filed Oct. 22, 1968, Ser. No. 14,106

Claims priority, application Italy July 8, 1968

Term of patent 7 years

Int. Cl. D9—04

U.S. Cl. D9—184

Fig.1

Fig. 2

Fig. 3

FIG. 1 is a top perspective view of a box for candy or the like showing my new design;

FIG. 2 is a top plan view thereof; and

FIG. 3 is an elevation of the side opposite that shown in FIG. 1.

The bottom is substantially plain and unornamented.
I claim:

The ornamental design for a box for candy or the like, as shown and described.
